William Isiah Stephens, Telford, Pa., assignor to Art Metal-Knoll Corporation, New York, N.Y., a corporation of Delaware

Continuation-in-part of design application Ser. No. 7,101, May 8, 1967. This application Sept. 23, 1968, Ser. No. 13,681

Term of patent 14 years

Int. Cl. D6—01

U.S. Cl. D15—1

FIG. 1 is a front perspective view of a chair or similar article showing my design;

FIG. 2 is a rear perspective view thereof.

The essential features of my design reside in those portions shown in full lines on the drawing.

This application is a continuation-in-part of my earlier filed pending application, Ser. No. 7,101, filed May 8, 1967, and now abandoned.

I claim:

The ornamental design for a chair or similar article, as shown and described.
